STAPLING MACHINE MAGAZINE

William A. Forrester, Herrin, Ill., assignor to International Staple and Machine Company, Herrin, Ill., a corporation of Pennsylvania

Application September 10, 1954, Serial No. 455,195

3 Claims. (Cl. 1—3)

This invention relates to improvements in stapling machines, and in particular is concerned with a stapling machine magazine which has means for minimizing jamming of staples, and release means for freeing the magazine and the jammed staple if jamming does occur.

The staple magazine of this invention is designed to accommodate a conventional stick of staples and can be used with stapling machines having stationary anvils or retractable anvils of the type disclosed in Schafroth Patent No. 2,469,054, assigned to International Staple and Machine Company. In both of these types of machines the magazine is designed to advance the stick of staples underneath a driving blade which drives the endmost staple in the stick which is situated underneath the driving blade. In this type of operation there has been trouble in the past due to jamming when the driving blade strikes the top of the staple. Such jamming, which may be due to slight irregularities in the staple stick in which some of the staples may be off-center, necessitates a laborious withdrawal of the magazine and the entire staple stick to clear the jammed staple.

By means of this invention, there has been provided a magazine which has a confining bar or crosshead cover plate at the end of the magazine adjacent the driving blade, and which has means for passing staples which would ordinarily jam the machine. This confining bar is provided with a recess under which the staples pass to be contacted by the driving blade. The recess will permit staples having a slight bulge on their crown to pass without jamming. This has been a source of trouble in the past. Further, at the end of the magazine in the driving blade region there is provided a wear plate situated directly underneath the confining bar and spaced therefrom so as to allow staples to pass therebetween. This wear plate has beveled corners and an angular bottom so that when the endmost staple is contacted by the driving blade there are no sharp protuberances upon which the staple can jam. This combination of the confining bar and wear plate effectively minimizes jamming problems which have been encountered in the staple machines heretofore made.

Further, the magazine of this invention is provided with a magazine release which biasedly holds the magazine in place in the stapling machine. By means of this biased relation, if jamming does occur, the magazine may be moved backwardly so as to permit the jammed staple to be removed and cleared from the machine. Further, if it is necessary to remove the magazine, the magazine release is so designed that this operation can be done by one hand without any complicated unlocking manipulation.

Accordingly, it is a principal object of this invention to provide a staple magazine having staple passing means at the end thereof which will substantially eliminate jamming.

It is a further object of this invention to provide a staple magazine having a crosshead comprising a confining bar and a wear plate through which the staples pass, and

2

wherein the confining bar and wear plate have means to pass slightly misaligned staples without jamming.

It is yet another object of this invention to provide a stapling magazine wherein a crosshead is provided comprising a confining bar which has means for passing staples thereunder which are slightly bulged on their crown without jamming.

Still a further object of this invention is to provide a crosshead for a stapling magazine wherein a confining bar which is adapted to be situated adjacent a driving blade has beveled means thereon so as to prevent jamming of the driving blade against the confining bar.

Yet another object of this invention is to provide a staple magazine having a wear plate at the end of the magazine which is situated adjacent the endmost staple adapted to be contacted by the driving blade, and in which the wear plate has slanted means at its corners so as to prevent jamming when the endmost staple is separated from the staple stick in the driving operation.

Still another object of this invention is to provide a staple magazine and magazine release which holds the magazine in a biased relation in the machine so that the magazine may yield against any forces tending to cause jamming and thereby facilitates clearing of jammed staples.

Still another object of this invention is to provide a staple magazine and a magazine release which holds the magazine locked in a biased manner, and wherein the magazine can be withdrawn against the biasing forces and thereby be removed from the stapling machine.

Yet a further object of this invention is to provide a staple magazine and release wherein the magazine is provided with a crosshead including a confining bar and wear plate having means to minimize the jamming of staples, and in which the magazine release holds the magazine in position in a yieldable manner so that jamming forces which might occur cause the magazine to be partially retracted so as to clear staples which might otherwise be jammed in the machine.

Further objects of this invention will appear to those skilled in the art and will further be apparent from the detailed description of this invention which follows.

For the purpose of description, one embodiment of the invention is illustrated in the accompanying drawings, but it is to be understood that this invention is not limited thereto.

In the drawings:

Figure 1 is a plan view of the staple magazine, the magazine release, and a magazine support;

Figure 2 is a view in side elevation of the device of Figure 1;

Figure 3 is a front end elevation of the device of Figure 2;

Figure 4 is a plan view of the magazine release;

Figure 5 is a view in side elevation of the magazine release;

Figure 6 is a view in side elevation of the rear portion of the staple magazine;

Figure 7 is an enlarged plan view of the front end of the staple magazine with the crosshead removed therefrom;

Figure 8 is a view in section taken on the line 8—8 of Figure 7;

Figure 9 is a view in side elevation of the wear plate;

Figure 10 is a view in front elevation of the wear plate;

Figure 11 is an enlarged plan view of the front end of the staple magazine showing in particular the crosshead construction and the confining bar;

Figure 12 is a view in side elevation of the crosshead portion of the staple magazine; and

Figure 13 is a view in section taken on the line 13—13 of Figure 12 showing the positional relationship of the

confining bar, the wear plate, and the track of the staple magazine.

Referring now to the drawings, and Figures 1 and 2 in particular, there are shown generally indicated four main elements. These elements are a magazine support 20 which acts as the staple machine leg or base, a magazine 21, a magazine wear plate 45, and a magazine release 23. The magazine support 20 is adapted to be attached to a retractible anvil stapling machine of the type described in the Schafroth Patent No. 2,469,054, but it is to be understood that this invention could be used with other conventional types of stationary anvil stapling machines, as well as any other type of stapling machine utilizing a conventional driving blade which contacts the crown of the staple.

The magazine support 20 is of a generally channel-shaped cross section and has two parallel upstanding side pieces 30 and 31 connected together at the bottom by a base 32. Medially situated upon side pieces 31 and 32 (Figs. 1 and 3) are upstanding flanged supports or lugs 33 and 34, respectively. Further, each of these flanged supports are provided with holes in which the axis is parallel to the base of the magazine support.

The side pieces 30 and 31 of the magazine support are further provided with vertical flanges at their front ends in which there are a plurality of connecting studs 35 so that the entire unit may be connected to the rest of the stapling machine which contains the operating parts for driving the stapling blade in a manner similar to that shown in Schafroth Patent No. 2,469,054.

The magazine 21 includes a frame 40 of a generally rectangular configuration, as shown in Figure 8, but wherein the top is left open in the center. A staple track 41 of U-shaped configuration is inverted and secured to the bottom of the frame by welding or the like in such a manner that the vertical legs point upwardly within the open section of the frame.

The lateral sides of the magazine frame 40 are provided with opposing flanges 42 and 43, as best appears in Figures 1, 6 and 8. These flanges provide a support for receiving the magazine release 23, as will appear more fully hereinbelow.

The forward end of the magazine frame 40 is specially formed so as to receive the wear plate 45. This is particularly shown in Figure 7 wherein it is seen that the front edges 36 on the sides of the magazine frame extend beyond the leading edge 37 of the bottom. Similarly, the inturned top edges of the magazine frame end at 38 rearwardly of the bottom side. This permits accommodation of the crosshead cover plate 44, as best shown in Figures 11, 12 and 13. The width of the cover plate 44 is slightly greater than the horizontal distance between the inturned edges of the top side of the magazine frame at 38 and the leading edge 37 of the bottom side so that a wear plate 45 can be accommodated in a flush position with the forward edge of said cover plate.

A recessed portion 46 is provided in the medial portion of the cover plate in order that slightly crowned staples may be accommodated without obstruction, as shown by the clearance provided in Figure 13. The cover plate is secured to the top of the magazine sides and the inturned flanges of the top side of the magazine frame by welding or the like, as appears in Figure 12.

The wear plate 45 is more particularly shown in Figures 9, 10 and 12 wherein it is seen that it is of a generally T-shaped configuration in inverted position with angularly disposed flanges 51 and 52 which prevent catching of the staples against the wear plate. The top of the wear plate is flat, but has beveled corners 53 and 54. These beveled corners prevent any catching of the individual staple as it is advanced through the magazine even though it may be misaligned or in a slightly askew position. This catching of the staple upon the wear plate on the sharp corners has been a considerable problem in the past,

and by means of this feature the problem has been greatly minimized.

As shown in Figures 1 and 11, after the wear plate has been assembled upon the magazine frame there is a space between the forward edge of the wear plate and the forward edges 36 of the sides of the magazine frame corresponding to slightly more than the width of the staple to be accommodated therebetween. The forward edges of the sides of the magazine abut against the interior parts of the stapling machine due to the biasing action of the magazine release. This abutment stops the forward movement of the magazine and causes it to be held firmly in place. It will also be noted that the crosshead cover plate 44 is beveled at 47 so that the staple driving blade cannot catch thereon in its downward movement and operating action.

The magazine release 23 is best shown in Figures 4 and 5 where it is seen to include opposed right angle flanges 61 and 62 which act as receiving elements for the operator's fingers. Connected to the flanges 61 and 62 at the bottom thereof is a base 63. The base 63 provides a tie between the two sides of the release. Both the flanges 61 and 62 are provided with pins 64 and 65. These pins are firmly secured to the flanges and are drilled at their ends so as to receive cotter pins 66 and 67, as best appears in Figure 1. This enables the magazine release to be positioned within the base 20 in such a manner that springs 68 and 69 can be placed thereon in a biasing position in which the springs are limited by the base supports 33 and 34, and pins 66 and 67.

Use

It is to be understood that in the use of this invention the magazine base or leg 20 is fastened to a stapling machine containing the operating mechanism for actuating a staple driving blade in the conventional manner. Thus, the base 20 is located by the pins 35 on the machine in such a manner that the driving blade is adapted to be driven downwardly in between pins 35 in the usual fashion.

In operation the magazine release 23 is first inserted in the base in such a manner that the pins 64 and 65 are inserted within the axial holes in the supports or lugs 33 and 34. After this has been done, springs 68 and 69 are placed over the pins and locked in place by cotter pins 66 and 67, respectively. This biases the flanges 61 and 62 in the direction of the arrow shown in Figure 1 so that these flanges abut against the supports 33 and 34.

After this operation has been effected, the operator withdraws the magazine release rearwardly in the opposite direction of the arrow shown in Figure 1 so that the magazine 21 can be inserted in such a manner that the flanges 42 and 43 pass between the magazine release flanges 61' and 62' and the supports 33 and 34. When this insertion has been accomplished and the base of the magazine rests upon the upper surface of the magazine support, the magazine is moved forwardly in the direction of the arrow until the forward ends of the sides of the magazine frame 41 abut against the stapling machine and are in firm contact therewith. At this time the magazine release 23 is released and the biasing action of springs 68 and 69 maintains, by the contact of the flanges 61' and 62' with the flanges 42 and 43 of the magazine, a locking condition for the magazine. However, by virtue of the biasing action of springs 68 and 69 a slight rearward movement against the force of the springs can be effected on the magazine should the staple driving blade contact the crosshead cover plate or meet a jammed staple.

The staple driving blade will contact the exposed staple when a staple stick is inserted upon the staple track 41 of the magazine. These staples in the staple stick are urged in the direction of the arrow, shown in Figure 1, by a conventional magazine pusher (not shown). The endmost staple at the forward end of the staple stick will fit between the leading edge of the crosshead cover plate

and the leading edges 36 of the sides of the magazine frame 40 so as to be free to be contacted by the staple driving blade in its downward operation.

Should any of the staples in the staple stick be slightly askew or otherwise misaligned, the beveled corners 53 and 54 of the wear plate 45 provide for ease in clearance when the endmost staple is contacted by the staple driving blade. Further, slight crowns or protuberances on the crown are permitted to pass without obstruction by the recess portion 46 of the crosshead cover plate 44. These features provide a highly satisfactory passage of staples to the staple driving blade without jamming.

Should jamming occur for any reason, however, the magazine 21 is adapted to be moved rearwardly against the biasing action of the spring so that a very easy clearing of the jammed staple can be effected. There are no complicated parts that are required to be operated to effect this operation and the simplicity of this feature is of great advantage.

When the magazine release is desired to be operated to permit removal of the magazine, this can be done by grasping the flanges 61 and 62 with the fingers of one hand and moving it in a direction rearwardly with respect to the stapling machine. This permits the magazine to be withdrawn rearwardly so that the flanges 42 and 43 can be slipped from underneath the supports 33 and 34 of the base which normally maintain it in a locked position to resist removal from the base. After this rearward movement has been effected, the magazine may then be withdrawn by lifting it out of the base.

Various changes and modifications may be made within the teachings of this invention, and such changes and modifications as will appear to those skilled in the art are to be included within the scope of the claims appended hereto.

What is claimed is:

1. A staple magazine assembly for use in a stapling machine, said assembly comprising a magazine, a base for supporting said magazine, a magazine release having biasing means cooperating with said base for urging said magazine against said stapling machine, and retaining

means on said base preventing movement of the magazine upwardly from the base while providing for limited movement in a direction against said biasing means.

5 2. A magazine assembly adapted for use in a stapling machine comprising a magazine having protruding elements on opposed sides thereof, a base for receiving said magazine having opposed lugs spaced from one another, and a magazine release movably supported within said base in contacting relationship with the protruding elements 10 of said magazine and having biasing means cooperating with said lugs for urging said magazine forwardly against said stapling machine.

15 3. A magazine assembly adapted for use in a stapling machine comprising a magazine having protruding elements on opposed sides thereof, a base for receiving said magazine having opposed lugs spaced from one another, and a magazine release disposable within said base in contacting relationship with the protruding elements of 20 said magazine and having biasing means cooperating with said lugs for urging said magazine forwardly against said stapling machine, said magazine being maintained in said base by said biasing force against vertical displacement by registering of said protruding elements beneath said lugs, said magazine being releasable by moving the magazine rearwardly against the biasing means until the 25 protruding elements are out of registration with said lugs.
